Primary Examiner — Susan E Krakower*Assistant Examiner* — Lisa A Grabenstetter(74) *Attorney, Agent, or Firm* — Gwendoline(57) **CLAIM**

The ornamental design for a brush head, as shown and described.

DESCRIPTION

FIG. 1 is perspective view of a brush head showing our new design, shown in a reduced scale and in environmental use;

FIG. 2 is a front view thereof;

FIG. 3 is a back view thereof;

FIG. 4 is a first side elevational view thereof;

FIG. 5 is a second side elevational view thereof;

FIG. 6 is a top plan view thereof; and,

FIG. 7 is a bottom plan view thereof.

The broken line portions of FIGS. 1-7 show unclaimed subject matter only and form no part of the claimed design. The broken line illustration of a brush handle in FIG. 1 shows unclaimed environment and forms no part of the claimed design.
